(57) **CLAIM**

The ornamental design for a light source module, as shown and described.

DESCRIPTION

FIG. 1 is a front view of a light source module of the present invention.

FIG. 2 is a rear view of the light source module of FIG. 1. FIG. 3 is a top plan view of the light source module of FIG. 1.

FIG. 4 is a bottom view of the light source module of FIG. 1.

FIG. 5 is a right side view of the light source module of FIG. 1.

FIG. 6 is a left side view of the light source module of FIG. 1.

FIG. 7 is a perspective view showing the front, top and right side of the light source module of FIG. 1.

FIG. 8 is a perspective view showing the front, bottom and right side of the light source module of FIG. 1; and,

FIG. 9 is alternate perspective view showing the front, bottom and right side of the light source module of FIG. 1. The features shown in dotted lines depict environmental subject matter only and form no part of the claimed design.
